UNITED STATES PATENT OFFICE.

HENRY A. VAN LIEW, OF SPRINGFIELD, NEW JERSEY, ASSIGNOR TO ORIENTAL SILK PRINTING COMPANY, OF NEW YORK, N. Y., A CORPORATION OF NEW JERSEY.

ORNAMENTED FABRIC AND METHOD OF PRODUCING THE SAME.

Application filed January 9, 1923. Serial No. 611,662.

To all whom it may concern:

Be it known that I, HENRY A. VAN LIEW, a citizen of the United States, and a resident of Springfield, in the county of Union 5 and State of New Jersey, have made and invented certain new and useful Improvements in Ornamented Fabrics and Methods of Producing the Same, of which the following is a specification.

10 My invention relates to a novelly ornamented fabric and the process of producing the same.

The roller printing process, due to its economical operation and high yardage per 15 machine, has largely displaced the hand or block printing process for the ornamentation of material. The size of a design that may be produced by the roller printing process is however quite limited, due to the 20 limited diameter of successful and practical printing rolls. In actual practice it has been found that a printing roll of approximately 20 to 24" in circumference is about the largest that can be successfully produced 25 and operated and therefore the printing of panels, large handkerchief squares or table covers comprising a single or unitary design of large size has heretofore been produced by the slow and necessarily costly block printing or hand decorating process.

It is accordingly an object of my invention to provide an ornamented fabric having 30 printed thereon a continuously recurring pattern of such size that it may be produced by a printing roll of ordinary circumference and two or more of which patterns or repeats of the printing roll will amalgamate and join together to form congruent, unitary designs of large size.

40 A further object is to provide a pattern or printing roll and a method whereby two or more impressions of the printing roll will amalgamate and join together to form a single, congruent and unitary design and thus provide for the economical printing by 45 the roller printing process of large panels or handkerchief squares, table covers, rugs, carpets, and various other articles heretofore considered impossible to produce by a 50 roller printing process and accordingly produced by a block printing or hand decorating method.

With the foregoing and other objects in 55 view, my invention resides in the novel, ornamented material or fabric illustrated in

the accompanying drawing and in the process and roller for producing the same, all as hereinafter described and claimed, and in such variations and modifications thereof as will be obvious to those skilled in the art to which my invention relates, it being understood that changes may be made within the scope of what is claimed without departing from the spirit thereof.

60 In the drawing accompanying this specification and forming a part thereof:

Figure 1 is a plan view of a pattern and developed view of a printing roller embodying the characteristic features of my invention;

Figure 2 is a plan view of a strip of material ornamented by the pattern of the printing roller illustrated in Figure 1 and by full lines illustrating the amalgamation of contiguous impressions or repeats into one enlarged, congruent and unitary design;

Figure 3 is a plan view of a somewhat different pattern and developed view of a printing roller having the particular pattern thereon; and

Figure 4 is a plan view of a fabric or strip of material ornamented by the printing roller as illustrated in Figure 3 and illustrating by full lines the manner in which three contiguous impressions amalgamate and join together to form one enlarged, congruent and unitary design.

Referring specifically to Figure 1, I have found that if a pattern A of such nature and characteristics be incorporated upon a printing roller B (Figure 1 representing a developed view thereof) and a continuous strip of material such as C in Figure 2 be printed or decorated thereby, there will be produced upon the continuous strip of material, an amalgamation of contiguous or adjacent impressions, the impression D thus amalgamating with the adjacent impression E to form the ornamented portion F of the material which contains a single, unitary and congruent design such as illustrated by the full lines in Figure 2. The material may accordingly be used for large handkerchief squares, table covers, etc., heretofore only produced by the slow and necessarily costly block printing process.

100 In like manner, I have found that this novel method and novelly ornamented material may be produced as illustrated in Figures 3 and 4, Figure 3 being a developed 105

view of a roller G bearing a novel and characteristic pattern H thereon. When the continuous strip material K is passed beneath and ornamented by this roller and pattern, then the individual repeats L, M and O will join together and amalgamate to form a single, congruent and unitary design R, the design R apparently possessing none of the outstanding characteristics of 10 the original pattern H, and being apparently composed of two overlapping and oppositely facing half moons S symmetrically arranged with respect to a centralized circle T.

15 Thus I have built up a single unitary and congruent design from three contiguous impressions of the printing roller, so that practically any size of unitary design may be produced, and carpets, table covers, rugs, 20 and similar articles may thus be economically produced by my novel roller printing process.

While I have illustrated my invention as being carried out with two and with three 25 repeats of the printing roller, it will be readily appreciated that four or more repeats may be thus joined together; nor do I wish to limit myself to the particular patterns illustrated, as it will be apparent that 30 other patterns may be developed which will lend themselves equally well to my novel process and novelly ornamented material.

My novel process of ornamenting or decorating cloth or material is of enormous value to the roller printing trade and it is 35 now possible to produce by the roller printing process a great many articles which have heretofore only been produced by the slow, cumbersome and accordingly expensive block printing method or actual hand 40 decoration, and having thus fully described my invention what I claim as new and desire to secure by Letters Patent is:

Apparatus for printing a design pattern upon a strip of fabric material consisting 45 of a roller having in relief upon its periphery a fractional section only of the pattern of the complete design, the lines of the design section upon the roller being symmetrical with relation to the median dimensions of the design section and the lines of the design section upon the roller having points which register with each other at the surface of the roller whereby the pattern section upon the roller is devoid of break. 50

Signed at New York, borough of Manhattan, in the county of New York and State of New York, this 5th day of January A. D. 1923.

HENRY A. VAN LIEW.
